UNITED STATES PATENT OFFICE.

GEORGE W. DAY, OF GASPORT, NEW YORK.

WATER-RELIEF VALVE.

No. 881,848.

Specification of Letters Patent. Patented March 10, 1908.

Application filed April 8, 1907. Serial No. 366,975.

To all whom it may concern:

Be it known that I, GEORGE W. DAY, a citizen of the United States, residing at Gasport, in the county of Niagara and State of New York, have invented certain new and useful Improvements in Water-Relief Valves, of which the following is a specification, reference being had to the accompanying drawings.

10 My invention relates to improvements in water-relief valves; and an object of my invention is to provide a valve of this character which will be simple in construction and efficient in operation, and which will keep the pressure of the system it controls uniform within narrow limits.

15 In the drawings illustrating the principle of my invention and the best mode now known to me of applying that principle, Figure 1 is a central vertical section; and Fig. 2 is a plan view.

The casing is two-part, the upper part *a* being screwed into the lower part *b*. The latter is provided with the inlet pipe-connection *c* and the outlet pipe-connection *d*, both of which are threaded. Extending axially through the valve casing is the stem or plunger *e* the lower end of which carries the disk valve *f* which is normally seated upon the valve-seat *g* made of any suitable material and firmly secured in the recess *h* above the outlet. Above the disk or collar *i* formed about midway of the stem is placed a cup washer or crimp *j* held down upon the flange *i* by the nut *k* between which and the cup washer is interposed an annular washer *m*. Upon the latter bears one end of a coil spring *n* the other end of which presses against the top of the upper part *a* of the valve-casing. The tension of this coil spring is varied by turning the upper part *a* into and out of the lower part *b*. Near the inlet opening the valve-stem is provided with a disk-like collar or flange *o* the interval between which and the wall of the casing is slight.

45 The operation is as follows: When the pressure of the system is greater than that for which the valve is set, the valve-stem is raised against the tension of the coil spring and the valve *f* leaves its seat, thereby permitting water to flow from the inlet to the outlet in order to relieve the pressure. The rush of the water past the edge of the flange or collar *o* forces the valve upon its seat before the pressure of the system has been decreased below the pressure for which the

valve is set; and the pressure in the system is thereby kept within narrow limits, which is the function of this type of valve. To the upper end of the valve-stem is pivotally secured an arm *p* formed with a cam face *q* which, when the arm is raised to the dotted line position of Fig. 1, bears against the top of the part *a*. By these means the valve-stem is raised to relieve the pressure to any desired extent.

I claim:

1. A water-relief valve consisting of a casting; a valve-stem mounted therein; a valve upon said valve-stem; a spring controlling said valve-stem; means actuated by the pressure of the water for opening said valve; and means upon said valve-stem and actuated by the water for closing the valve; the last named means being separate from said valve and on the side thereof opposite from the opening controlled thereby.

2. A water-relief valve consisting of a valve casing; a valve-stem mounted therein; a valve upon said valve-stem; means for holding said valve closed against the pressure of the water; means actuated by the pressure of the water for opening said valve; and means for closing the valve after it has been opened by the pressure of the water; said last named means being separate from the first named means and from said valve and on the side thereof opposite from the opening controlled thereby.

3. The combination in a water-relief valve of a valve casing provided with a valve-seat; a valve-stem mounted in said casing; a valve upon said valve-stem; means for holding said valve upon said valve-seat; means actuated by the pressure of the water for raising said valve from said valve-seat against the action of the first named means; and a flange upon said valve-stem between said valve and the inlet to said casing; said flange being separated from the inner wall of said casing by a narrow interval and serving to seat the valve after it has been opened by an excess of pressure.

In testimony whereof I have hereunto set my hand this second day of April, A. D. 1907, in the presence of the two undersigned witnesses at Lockport, in said county and State.

GEO. W. DAY.
